US0D1009944S

(12) **United States Design Patent** (10) **Patent No.:** **US D1,009,944 S**
(45) **Date of Patent:** **** Jan. 2, 2024**

(54) **ROTARY DRILLING RIG**

(71) **Applicant:** **JiangSu XCMG Construction Machinery Research Institute LTD.,**
Jiangsu (CN)

(72) **Inventors:** **Xuemei Zong**, Jiangsu (CN); **Younian Fang**, Jiangsu (CN); **Mingjiang Wang**,
Jiangsu (CN)

(73) **Assignee:** **JiangSu XCMG Construction Machinery Research Institute LTD.,**
Jiangsu (CN)

(**) **Term:** **15 Years**

(21) **Appl. No.:** **29/735,423**

(22) **Filed:** **May 21, 2020**

(30) **Foreign Application Priority Data**

(57) **CLAIM**

The ornamental design for a rotary drilling rig, as shown and described.

DESCRIPTION

FIG. 1 is a right-front-top perspective view of a rotary drilling rig showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a right-rear-top perspective view thereof;
FIG. 8 is a left-front-top perspective view thereof;
FIG. 9 is a left-rear-top perspective view thereof;
FIG. 10 is a right-front perspective view thereof;
FIG. 11 is a right-rear perspective view thereof;
FIG. 12 is a left-front perspective view thereof; and,
FIG. 13 is a left-rear perspective view thereof.
